TWO-WAY DISK PLOW

Harry A. Pursche, Gardena, Calif.

Application June 20, 1949, Serial No. 100,107

17 Claims. (Cl. 97—32)

1

This invention relates to plows, and is particularly directed to a two-way disk plow construction.

In my prior applications for two-way plows, Serial Nos. 760,846, 780,417, 18,252, 38,352, and 44,338, I have shown and described improved forms of two-way plow constructions which are particularly adapted for use on conventional mold board plows. Each of these devices employs one or more right-hand plowshares and one or more left-hand plowshares. It is well known that certain types of soil may be plowed more readily and efficiently with disk-type plows than with mold board plows.

Accordingly, it is the principal object of the present invention to provide an improved form of two-way plow using ground-engaging disks.

Another object is to provide a two-way disk plow which is particularly adapted for use in conjunction with a tractor provided with draft links of the Ford-Ferguson type.

Another object is to provide a two-way disk plow having a carrier pivotally mounted on a support frame and a pair of ground-engaging disks on the carrier, one in advance and one to the rear of the pivotal connection between the carrier and support frame.

Another object is to provide a two-way disk plow having one or more ground-engaging disks, each of the disks being operative for producing both right-hand and left-hand furrows.

Another object is to provide a two-way disk plow having an inclined carrier mounted for turning movement about a vertical axis, the carrier being provided with spaced ground-engaging disks, the inclination of the carrier serving to compensate for the inclined position of the tractor on which it is carried when the side wheels of the tractor alternately roll in a left-hand furrow and in a right-hand furrow.

Another object is to provide a two-way disk plow having a carrier mounted for pivotal movement about a substantially vertical axis and including a pair of ground-engaging disks, each carried on posts turnably mounted on the carrier.

Further objects and advantages will appear hereinafter.

In the drawings:

Figure 1 is a side elevation partly broken away showing a preferred embodiment of my invention.

Figure 2 is a plan view thereof, the tractor being omitted, and showing the ground-engaging disks in position to form a left-hand furrow.

Figure 3 is a view similar to Figure 2, the

2

ground-engaging disks being shifted to produce a right-hand furrow.

Figure 4 is a plan view taken substantially on the lines 4—4 as shown in Figure 1 and illustrating the ground-engaging disks in one plowing position.

Figure 5 is a view similar to Figure 4 showing the ground-engaging disks in the other plowing position.

Figure 6 is a rear view of the plow assembly and tractor showing the position of the parts when the left-hand tractor wheels roll in the furrow.

Figure 7 is a view similar to Figure 6 showing the position of the parts when the right-hand tractor wheels roll in the furrow.

Figure 8 is a sectional detail partly broken away showing the connection between the vertically extending trunnion and the inclined carrier.

Figure 9 is a sectional plan view taken substantially on the lines 9—9 as shown in Figure 8.

Figure 10 is a sectional elevation taken substantially on the lines 10—10 as shown in Figure 4 and showing the structure for connecting the ground-engaging disks to the carrier.

Figure 11 is a sectional detail partly broken away taken substantially on the lines 11—11 as shown in Figure 10.

Figure 12 is a sectional detail showing a typical ball joint connection between one of the crank arms and shiftable control element.

Referring to the drawings, the two-way plow assembly generally designated 10 is adapted to be supported from a conventional tractor 11.

The tractor may be provided with rearwardly extending draft links 12 and a central compression link 13. The links 12 and 13 may be of the general type known in the art as Ford-Ferguson links. A supporting frame 14 is carried by the links 12 and 13 and may be raised and lowered relative to the tractor by means of hydraulically actuated cranks 15 provided on the tractor. These cranks act through lift rods 16 to raise and lower the links 12.

A carrier 17 is pivotally supported from the member 14 by means of a rotatable trunnion 18. The carrier is provided with support assemblies 19 and 20 and each of the assemblies carries a rotatable ground-engaging disk 21 and 22. A furrow wheel 23 is also provided on the carrier 17. When the frame 14 and carrier 17 are lowered into plowing position the forward disk 21 and rear disk 22 engage the soil to turn a furrow. A right-hand furrow is turned when the carrier is swung so that the disks take the position shown

in Figure 5, and a left-hand furrow is turned when the disks take the position shown in Figure 4. Since the wheels on one side of the tractor roll in the furrow when plowing in one direction, and since the wheels on the other side of the tractor roll in the furrow when plowing in the other direction, the carrier 17 is mounted at an angle with respect to the trunnion 18 to compensate for the tilted position of the tractor in each case.

Considering the construction of the preferred form of my invention in more detail, the support frame 14 includes a central beam 24 extending in the direction of movement of the plow. The beam 24 is connected at its forward end to a cross-beam 25 which in turn is provided with axially aligned and oppositely extending support pins 26. These pins are pivotally engaged by the draft links 12 extending from the tractor 11. An upwardly extending bracket 27 is provided centrally of the frame 14 and is connected to the tractor link 13 by means of an extension piece 28. The extension piece is connected to the link 13 by means of bolts 29 and is pivotally attached to the bracket 27 by means of a pivot pin 30.

A tubular bearing shell 31 is secured to the beam 24 near its rearward end, and this shell is mounted substantially vertically. The trunnion 18 is turnably mounted within this bearing shell 31 as is clearly shown in Figure 8. The upper end of the trunnion is squared as shown at 32 and is received in a square recess formed in the double-ended control crank 33. The squared end 32 on the trunnion 18 may be received as a press fit within the central recess within the member 33, and accordingly, the member 33 prevents the trunnion from dropping downwardly through the bearing shell 31. Any other suitable means may be provided if desired supporting the trunnion against downward movement. The lower end of the trunnion 18 is provided with an enlarged head 34 which extends beyond the diameter of the bearing shell 31. This head 34 is received within a central recess 35 provided in the carrier 17. A horizontal pivot pin 36 connects the head 34 to the carrier 17. Arcuate slots 37 are provided in the head 34 for reception of friction clamp bolts 38 which extend through the carrier 17 and through the arcuate slots 37. The carrier 17 is mounted at an angle with respect to the substantially vertical axis 39. This angle is adjustable by means of the provision of the slots 37 and clamp bolts 38. The carrier may be further fixed in adjusted position by means of the set screws 40 and lock nuts 41.

A tubular column 42 is fixed by any convenient means such as welding at the forward end of the carrier 17. A post 43 is turnably mounted within this column 42 and carries an angularly positioned bifurcated support 44 at its lower end. The upper end of the post 43 is squared as shown at 45 and is received within a square recess provided in the crank 46. A set screw 47 prevents disassembly of the crank 46 and post 43. A swivel block 48 is mounted between the opposed sides of the bearing support 44 and is pivotally attached thereto by means of clamping bolt 49. The block 48 is provided with an arcuate recess 50 which receives clamping bolt 51. The nonrotary axle 52 of the ground-engaging disk 21 is fixed on the block 48 by means of nut 53. A bearing assembly (not shown) is provided within the housing 54 for rotatably supporting the ground-engaging disk 21 on the stationary axle 52. From the above description it

will be understood that the inclination of the axle with respect to the post 43 may be adjusted by swinging the block 48 between the sides of the bearing support 44. The clamping of the block 48 between the sides of the bearing support 44 holds the block in adjusted position, and this action is supplemented by means of the set screw 55 which is mounted on a transverse bar 56 extending between the sides of the bearing support 44.

The ground-engaging disk 22 is carried on the lower end of the post 57, and the mounting of this post and its associated disk is substantially identical to that just described in connection with the post 43 and disk 21. The crank 58 is secured to the upper end of the post 57 in the same manner as that described in connection with crank 46 and post 43. From this description it will be understood that the ground-engaging disks 21 and 22 may be turned or swiveled about their supporting posts in order to change the angle of attack of the disks with respect to the soil.

A double arm 59 is fixed to the bearing shell 31, and the extending ends of this arm are adapted to be connected by means of the links 60 and 61 to the cranks 46 and 58 respectively. Each of the links 60 and 61 is provided with a ball joint assembly 62 at each end. Each of the ball joint assemblies includes a laterally extending pin 63 which may be clamped to the arm 59 or to the cranks 46 or 58. As shown in Figure 12 the ball joint assembly 62 affords means for attaching the end of the link 60 to the crank 46. A slot 64 is provided in the crank 46, and the pin 63 extends through the slot. The pin may be anchored at any point on the slot by means of the nut 65. The crank 58 is similarly slotted at 66, and the ends of the double arm 59 may be slotted as shown at 67 and 68. Since the arm 59 is fixed on the bearing shell 31, it does not turn; movement of the carrier 17 about the axis of the trunnion does not move the arm 59, but such movement of the carrier 17 results in turning of the posts 43 and 57, thereby changing the relative positions of the disks 21 and 22.

Means are provided for swinging the carrier about the axis of the upright trunnion 18, and as shown in the drawings this means includes the double control arm 33 which is fixed to the upper end of the trunnion as described above. A first pair of links 69 is connected to one end of the double arm 33, and a second similar pair of links 70 is connected to the other end of the arm. The pair 69 includes links 71 and 72 connected by pivot 73, and the pair 70 includes links 74 and 75 connected by pivot 76. Link 72 is connected to double arm 33 by means of pivot pin 77, and link 75 is connected to double arm 33 by means of pivot pin 78. Link 71 is connected by pivot pin 79 to the stationary element 80 carried on the cross-beam 25. Similarly, link 74 is connected by pivot pin 81 to the member 82. A stop element 82 on the link 72 engages the link 71 to limit the extent of pivotal motion around the pivot 73. Similarly, a stop element 83 is provided on the link 75 which engages the link 74 to limit pivotal motion in one direction about the pivot 76. Thus, the pair of links 69 form a stiff-leg or strut as shown in Figure 2, while the pair of links 70 perform the same function in Figure 3. The pair of links 69, therefore, serves to provide a stop or latch to maintain the ground-engaging disks 21 and 22 in position for turning a left-hand furrow, while the links 70 provide a stop or latch for

holding the disks in position for turning a right-hand furrow.

A tension spring 84 is preferably secured to the links 72 and 75, and the action of this spring is to urge both of the links toward stiff-arm position. A power cylinder assembly 85 is provided for moving the link pairs 69 and 70 between the positions shown in Figures 2 and 3. This power cylinder assembly includes a hydraulic cylinder 86 having suitable inlet and outlet hydraulic lines 87 and 88 at its opposed ends. These hydraulic lines are flexible and are connected to a hydraulic pump and control assembly on the tractor, not shown. A continuous piston rod 89 extends through both ends of the cylinder 86. A piston 90 is reciprocable within the cylinder so that the piston rod 89 may be extended in either direction if desired. A clevis 91 is mounted on one end of the piston rod 89 for engaging the link 71, and a similar clevis 92 is mounted on the other end of the piston rod 89 for engaging the link 74. Each of the clevises may be provided with a contact roller 93 to reduce friction against the side of the links 71 and 74. When hydraulic fluid is admitted into the line 88 the clevis 92 is extended so that the links 74 and 75 assume an angle position and the links 71 and 72 assume the stiff-leg position. When hydraulic fluid is admitted through the line 87 the clevis 91 is extended so that the links 71 and 72 take an angle position and the links 74 and 75 assume the stiff-leg position. Movement of the piston rod 89, therefore, acts through the link pairs 69 and 70 to shift the double crank 33 and thereby shift the carrier 17 between the positions shown in Figures 2 and 3.

The adjustments above described between the ends of the links 69 and 61 and the arms 46, 53 and 59 afford means for changing the angular position of the disks 21 and 22 with respect to the position of the carrier 17. Such adjustment is desirable to compensate for wear and consequent reduction of diameter of the disks 21 and 22.

The furrow wheel 23 is carried at the lower end of a bifurcated post 94, and this post is adjustably mounted in the crank arm 95 carried on the pivot pin 96. The axes of the posts 43 and 57, the axis of the trunnion 18, and the axis of the pivot pin 96 are all contained in the same plane. The carrier 17, therefore, may take the form of an elongated beam having a longitudinal axis of symmetry. The pivot pin 96 connects the crank arm 95 to the carrier 17. A set screw 97 may be provided for adjusting the height of the post 94 with respect to the arm 95. A control arm 98 is formed integrally with the arm 95 and may be connected by means of link 99 to the stationary arm 100 fixed on the bearing shell 31. The link 99 serves to maintain the arms 98 and 100 in parallel relationship and consequently maintains the arm 95 and furrow wheel aligned with the direction of travel of the plow. As shown clearly in Figures 4 and 5 the furrow wheel 23 is on one side of the central trunnion 18 when the disks are turning a left-hand furrow and is on the other side of the trunnion 18 when the disks are turning a right-hand furrow. The wheel 23, therefore, is in position to roll in the furrow formed by the disks regardless of whether a right-hand or left-hand furrow is being turned. The function of the furrow wheel 23 is to prevent variation in cutting depth of the ground-engaging disks 21 and 22.

In operation the tractor is driven to the field

with the plow assembly 10 in elevated position as shown in Figure 1 with the disks 21 and 22 and the furrow wheel clear of the ground level. When the field to be plowed is reached the operator lowers the draft links 12 in the usual manner to enable the disks 21 and 22 to enter the ground. The first furrow may be made with the disks in either right-hand or left-hand position. Assuming that a left-hand furrow is formed initially, the power cylinder assembly 85 is actuated so that the carrier is swung to the position shown in Figures 2 and 4. The tractor is then driven from one end of the field to the other, forming a left-hand furrow. The links 12 are then raised to lift the plow assembly 10 out of the ground, the tractor is turned around, and the wheels on the right-hand side of the tractor are driven into the furrow just formed. The power cylinder assembly 85 is then actuated to shift the carrier 17 to the position shown in Figures 3 and 5. The disks 21 and 22 are then lowered into ground-engaging position and the tractor is driven back across the field, forming a right-hand furrow. The position of the tractor and plow assembly at this point in the cycle of operations is illustrated in Figure 7. The tractor continues to the end of the furrow, the plow assembly is lifted, the tractor turned around, and the wheels on the left side of the tractor are engaged in the furrow just completed. The carrier is shifted so that the disks 21 and 22 again turn a left-hand furrow. The plow assembly is lowered into the ground and the tractor is driven back across the field. The position of the tractor and plow assembly at this point in the cycle of operations is shown in Figure 6.

It will be observed from consideration of Figures 6 and 7 that the inclined position of the carrier 17 with respect to the trunnion 18 compensates for the inclined position of the tractor when the wheels on one side or the other roll in the furrow. The disks 21 and 22 extend for substantially the same distance into the soil when they are in either operative position.

Having fully described my invention, it is to be understood that I do not wish to be limited to the details herein set forth, but my invention is of the full scope of the appended claims.

I claim:

1. In a two-way disk plow, the combination of a carrier, a pair of spaced parallel posts on the carrier, a ground engaging disk rotatably mounted upon the lower portion of each of said posts, means for pivotally supporting the carrier for turning movement about a substantially vertical axis intermediate said posts, means for adjusting the angular inclination of the carrier with respect to said axis, and means for turning each of the posts relative to the carrier.

2. In a two-way disk plow, the combination of a carrier, a pair of spaced posts on the carrier, a ground engaging disk rotatably mounted upon the lower portion of each of said posts, a support member and cooperating parts for pivotally supporting the carrier on the support member for turning movement about a substantially vertical axis intermediate said posts, a furrow wheel pivotally mounted with respect to the carrier, the pivotal axis of the furrow wheel, the pivotal axis of the carrier, and the axes of said posts lying in a common plane, and linkage means on the carrier for maintaining the furrow wheel aligned in the direction of travel of the plow.

3. In a two-way disk plow, the combination of a support member, a trunnion turnably mounted on the support member about a substantially ver-

tical axis, a sloping carrier mounted on the trunnion at an angle thereto, a pair of disk-supporting posts turnably mounted on the carrier, a ground-engaging disk rotatably mounted upon the lower portion of each of said posts, means for shifting the carrier about said substantially vertical axis, and means for turning the posts relative to the carrier.

4. In a two-way disk plow, the combination of a support member, a trunnion turnably mounted on the support member about a substantially vertical axis, a sloping carrier mounted on the trunnion at an angle thereto, a pair of disk-supporting posts turnably mounted on the carrier on opposite sides of said trunnion, a ground-engaging disk rotatably mounted upon the lower portion of each of said posts, means for shifting the carrier about said substantially vertical axis, and means for turning the posts relative to the carrier.

5. In a two-way disk plow, the combination of a longitudinal support beam extending in the direction of travel, a trunnion turnably mounted on the rear end of the support beam about a substantially vertical axis, a carrier mounted on the trunnion, a pair of disk-supporting posts turnably mounted on the carrier on opposite sides of said trunnion, a ground-engaging disk rotatably mounted upon the lower portion of each of said posts, means for shifting the carrier about said substantially vertical axis, and means for turning the posts relative to the carrier.

6. In a two-way disk plow, the combination of a support member, a trunnion turnably mounted on the support member about a substantially vertical axis, a carrier mounted at an angle on the trunnion, a pair of disk-supporting posts turnably mounted on the carrier on opposite sides of said trunnion, a ground-engaging disk rotatably mounted upon the lower portion of each of said posts, means for shifting the carrier about said substantially vertical axis, and means for turning the posts relative to the carrier.

7. In a two-way disk plow, the combination of a support member, a trunnion turnably mounted on the support member about a substantially vertical axis, a carrier adjustably mounted at an angle on the trunnion, a pair of disk-supporting posts turnably mounted on the carrier on opposite sides of said trunnion, a ground-engaging disk rotatably mounted upon the lower portion of each of said posts, means for shifting the carrier about said substantially vertical axis, and means actuated by the shifting means for turning the posts relative to the carrier.

8. In a two-way disk plow, the combination of a longitudinal support beam extending in the direction of travel, a carrier, a pivotal element supporting the carrier on the rear end of the support beam, a pair of disk-supporting posts turnably mounted on the carrier on opposite sides of said pivotal element, a ground-engaging disk rotatably mounted upon the lower portion of each of said posts, means above the support beam for pivoting the carrier about the axis of the pivotal element, and means below the support beam actuated by the pivoting means for turning the posts relative to the carrier.

9. In a two-way plow, the combination of a carrier, a pair of ground-engaging disks, spaced elements on the carrier mounting the disks for rotation relative to said elements, means for piv-

totally supporting the carrier for turning movement about a substantially vertical axis, power means for shifting the carrier about said vertical axis, said power means including two pairs of links, the links of each pair being pivotally connected, one link of each pair being also connected to a stationary member, the other link of each pair being operatively connected to said carrier, stop means on each pair of links for limiting relative pivotal movement therebetween in one direction, and a power cylinder assembly on the support member selectively engageable with each pair of links.

10. In a two-way plow, the combination of a carrier, a pair of ground-engaging disks, spaced elements on the carrier mounting the disks for rotation relative to said elements, means for pivotally supporting the carrier for turning movement about a substantially vertical axis, said means including a support member pivotally connected to said carrier, a crank fixed relative to the carrier, power means on the support member for shifting the carrier about said vertical axis, said power means including two pairs of

links, the links of each pair being pivotally connected, one link of each pair being also connected to the support member, the other link of each pair being pivotally connected to said crank, stop means on each pair of links for limiting relative pivotal movement therebetween in one direction, and a power cylinder assembly on the support member selectively engageable with each pair of links.

11. In a two-way plow, the combination of a carrier, a pair of ground-engaging disks, spaced posts turnably mounted on the carrier, a ground-engaging disk carried by each of said posts, means for pivotally suspending the carrier for turning movement about a substantially vertical axis, said means including a longitudinally extending beam pivotally connected at its rear end to said carrier, a crank fixed relative to the carrier, power means above the support beam for actuating the crank to shift the carrier about said vertical axis so that the forward end of the carrier may pass under the support beam, and mechanical linkage means below the support beam operatively connecting the posts and said support beam whereby shifting of the carrier relative to the support beam acts to shift the posts relative to the carrier.

12. In a two-way disk plow, the combination of: a carrier, a pair of spaced posts on the carrier, a ground-engaging disk rotatably mounted on the lower portion of each of said posts, a longitudinal support beam extending in the direction of travel, pivot means at the rear end of said longitudinal beam supporting the carrier at a location between said posts, a furrow wheel pivotally mounted on the rearmost portion of the carrier, the pivotal axis of the furrow wheel, the pivotal axis of the carrier, and the axes of said posts lying in a common plane, power means for swinging the carrier relative to said longitudinal beam, and linkage means on the carrier for maintaining the furrow wheel aligned with the direction of travel of the plow.

13. A two-way disk plow attachable to a wheel tractor having hydraulically elevatable draft links, comprising in combination: a plow frame, means for connecting the plow frame to the draft links, a carrier, pivot means connecting the carrier to the plow frame for oscillatory movement about a substantially vertical axis, power means for swinging the carrier about said axis, ground-engaging disks rotatably mounted on the carrier,

means for adjusting the angular inclination of the carrier with respect to said axis, said pivot means being located on the longitudinal axis of the tractor whereby the inclination of the carrier may compensate for the inclination of the plow frame when certain of the tractor wheels roll in a furrow, and thereby equalize the cutting depth of said ground-engaging disks.

14. A two-way disk plow attachable to a wheel tractor having hydraulically elevatable draft links, comprising in combination: a plow frame, means for connecting the plow frame to the draft links, a carrier, pivot means connecting the carrier to the plow frame for oscillatory movement about a substantially vertical axis, power means for swinging the carrier about said axis, positive mechanical latch means for holding the carrier in either of two operative positions, ground-engaging disks rotatably mounted on the carrier, means for adjusting the angular inclination of the carrier with respect to said axis, said pivot means being located on the longitudinal axis of the tractor whereby the inclination of the carrier may compensate for the inclination of the plow frame when certain of the tractor wheels roll in a furrow, and thereby equalize the cutting depth of said ground-engaging disks.

15. A two-way disk plow attachable to a wheel tractor having hydraulically elevatable draft links, comprising in combination: a plow frame, means for connecting the plow frame to the draft links, a carrier, pivot means connecting the carrier to the plow frame for oscillatory movement about a substantially vertical axis, power means for swinging the carrier about said axis, ground-engaging disks rotatably mounted on the carrier, the carrier being mounted at an angle to said axis, said pivot means being located on the longitudinal axis of the tractor whereby the inclination of the carrier may compensate for the inclination of the plow frame when certain of the tractor wheels roll in a furrow, and thereby equalize the cutting depth of said ground-engaging disks.

16. A two-way disk plow attachable to a wheel tractor having hydraulically elevatable draft links, comprising in combination: a plow frame, means for connecting the plow frame to the draft links, the plow frame having a support beam extending longitudinally of the tractor and centrally thereof, a carrier, a pair of spaced posts

on the carrier, a ground-engaging disk rotatably mounted upon the lower portion of each of said posts, means for pivotally supporting the carrier on the rear end of the longitudinal beam for turning movement about a substantially vertical axis intermediate said posts, the carrier being mounted at an angle to said axis, said pivot means being located on the longitudinal axis of the tractor whereby the inclination of the carrier may compensate for the inclination of the plow frame when certain of the tractor wheels roll in a furrow, and thereby equalize the cutting depth of said ground-engaging disks.

17. A two-way plow attachable to a wheel tractor having elevatable support means, comprising in combination: a plow frame, means for connecting the plow frame to the support means, a carrier, pivotal means connecting the carrier to the plow frame for oscillatory movement about a substantially vertical axis, power means for swinging the carrier about said axis, ground-engaging tools mounted on the carrier, means for adjusting the angular inclination of the carrier with respect to said axis, said pivotal means being located on the longitudinal axis of the tractor whereby the inclination of the carrier may compensate for the inclination of the plow frame when certain of the tractor wheels roll in a furrow, and thereby equalize the operating depth of said ground-engaging tools.
